UNITED STATES PATENT OFFICE.

HENRY PRICE BALL, OF SCHENECTADY, NEW YORK, ASSIGNOR OF ONE-HALF TO
SAMUEL INSULL, OF CHICAGO, ILLINOIS.

ART OF PERFORATING MUSIC-STRIPS.

964,951.

Specification of Letters Patent. Patented July 19, 1910.

Application filed March 28, 1904. Serial No. 200,277.

To all whom it may concern:

Be it known that I, HENRY PRICE BALL, a citizen of the United States, residing at Schenectady, county of Schenectady, State 5 of New York, have invented an Improvement in the Art of Perforating Music-Strips, of which the following is a specification.

Music strips have heretofore been perforated by hand or through the instrumental- 10 0 city of a series of mechanically driven punches, controlled in their action by mechanical, pneumatic or electrical devices.

The production of music strips by hand is very slow, laborious and expensive, and 15 by mechanical devices, while much faster, thereby decreasing the cost of production, is unsatisfactory owing principally to the fact that the mechanical devices used are not able to exactly record, by a series of perforations, 20 the physical acts of a performer in striking notes, for example upon the keyboard of a piano or other musical instrument. As for instance, it has been found, the movement 25 of the fingers of a performer may be so quick, that the mechanical perforating device employed cannot respond to such movement, and will therefore fail to produce the required perforations. Further, a note may 30 be repeated so quickly, the mechanical devices employed will not form a series of 35 separate round holes indicative of successive notes played, *i. e.*, reproductions of the same note, but will produce an elongated hole, or otherwise, a perforation such as is commonly 40 made to produce, and which represents, a sustained note. Further, the perforating mechanism heretofore employed, must be initially set or adjusted for each different 45 musical composition to be perforated in a music strip, which act requires the expenditure of time, and materially adds to the cost of the production of the music strip. Further, in order to prevent alterations in the musical score as perforated, from that 50 played and due to the absence of a definite mathematical-mechanical relation between the acts of the performer and the responsive acts of the perforating mechanism, complicated corrective mechanism is necessary.

My invention is intended to overcome the 55 difficulties heretofore found in exactly recording in a music strip by a series of perforations, the physical acts of the performer,

and is based upon the following proposition, 55 namely:

The movements of a performer's fingers on a keyboard are very erratic when considered with respect to the regularity of movement of a perforating machine. For example, while the performer may strike, 60 say 300 repetitions a minute, the interval of time between each stroke will not be exactly 1/300 of a minute, but will vary from this amount a little more or less. The movement 65 of his fingers in striking the keys will also vary, for example, his fingers may hold the key down for a greater or less proportion of the time between the successive downward movements of the same key. It is to care 70 for these and similar idiosyncrasies in the performer's movements that I have devised the method herein described.

In this specification I will describe my improvement in the art of perforating a 75 music strip as resulting from the acts of a performer in striking the keys of a keyboard. I wish it understood, however, that the initial movement which results in the movement of the perforating mechanism, 80 may be caused by the physical effects of a master strip or commercial music strip operating through the usual tracker-board and pneumatic or electrically actuated mechanism.

In a series of applications heretofore filed 85 by me, I have fully described various forms of mechanism for perforating music strips in all of which a timing device is used, and whereby successive impulses given the same key will result in a succession of independent 90 perforations, with a given amount of unperforated material between such perforations, so that when such music strip is used over a tracker-board to reproduce the original tones, they will be as distinct and separate 95 as when first played, in fact the same as played by the performer. I will therefore in this application give but a general description of the different types of perforating mechanism which may be used to 100 carry my invention into effect.

In the drawings: Figure 1 is a front elevation of a perforating mechanism. Figs. 2, 3 and 4, are vertical sections on the line A—A of Fig. 1, and illustrate the different 105 positions of the parts during the movement

of a punch in making a perforation. Fig. 5 is a plan view of a music strip having rack hole perforations, joined perforations and separate perforations. Fig. 6 is a side elevation showing a modification of my invention. Fig. 7 is a similar view showing another modification. Fig. 8 is a vertical section through a piano and perforating mechanism, and illustrating how the perforating mechanism may be actuated by the movement of the piano action. Figs. 9 and 10 are corresponding views, showing a perforating mechanism and controlling means energized either by means of a weight or an electric device. Fig. 11, an enlarged side view of the hammer mechanism and controlling valve shown in Fig. 10. Figs. 12 and 13 are respectively a vertical and a horizontal section through the controlling valve.

20 Referring to the drawings:

I will first generally describe the perforating mechanisms shown in Figs. 1, 2, 3 and 4.

20 indicates one of the keys of a piano. At the rear end of such key is a rod 21, connected at its upper end to a pivoted lever 22. Secured to the rear end of this lever is a cord 23, which is connected at its upper end to the pivoted bell cranks 24, 25. Bell cranks 24, 25, control the action of the 30 punching mechanism, that is to say, a pair of such bell cranks is employed with each punch, and manifestly there will be as many punches as there are notes to be perforated.

I have shown the keys of a piano as the 35 means employed for moving the bell cranks 24, 25, which control the punches. As previously stated, I may substitute for such keys, any mechanical device actuated by a master roll or a commercial roll, for controlling the action of the perforating mechanism.

The perforating mechanism employed, 40 consists of a shaft 26, which I term the high speed shaft, and which is driven by a gear 27 in mesh with gear 28 on shaft 29, which shaft I term the slow speed shaft. Motion is given to shaft 29 through a motor (not shown) transmitting power through pulley 30, belt 31, and pulley 32 on shaft 29.

50 The high speed shaft 26 is arranged to make four revolutions to one of the shaft 29. Located on shaft 26 are series of eccentrics 33, each carrying a punch 34, arranged to reciprocate through a die seat 35, over which the music strip 36 is progressively moved.

The music strip 36 is adapted to be given 55 a forward movement by means of a friction roll 37, which is driven by shaft 38, interposed between the high speed shaft 26 and roll 37. It will thus be seen, that the movement of the paper forward has a direct relation to the speed of the shaft 26. The arrangement is preferably such that the 60 music strip will make a forward movement

of one-twentieth of an inch for each complete revolution of the high speed shaft 26.

The mechanism shown in the various figures for moving the music strip, is designed to give the strip a step by step forward movement, the strip being continuously wound from roll 39 onto roll 40. I do not, however, limit myself to this method of moving the music strip, as it may be given a continuous forward movement, as is illustrated and described in my Patent No. 778,835, dated January 3, 1905.

How the music strip is moved is not essential, provided it be given a definite forward movement having a mathematical relation to the high speed shaft 26.

Mounted on and secured to the high speed shaft 26, are the toothed wheels 41. These wheels are located between the eccentrics 33, and are each provided with a single tooth.

Pivottally mounted on each eccentric 33 and over a toothed wheel 41, is a spring pressed latch 42. When such latch is out of engagement with the toothed wheel 41, as shown in Fig. 2, no movement will be imparted to the eccentric 33 by the rotation of the shaft 26, but on the other hand, when a latch is in engagement with a toothed wheel, as shown in Fig. 4, movement will be given to an eccentric which will reciprocate the 95 punch 34, carried by it.

The position of each latch 42, is controlled by means of a pivoted trip lever 43. The upper end of a trip lever 43 is situated in the path of movement of the periphery of 100 a cam 44 on shaft 29. Mounted on and secured to the shaft 29 between the cams 44 are the toothed wheels 45 each wheel having four teeth, and pivoted on each cam 44 is a spring pressed latch 46. The position of 105 these latches 46 are controlled by the bell cranks 24, 25, as will be described.

Referring now to Fig. 5: This figure represents a portion of a music sheet. At the top of the figure are uniformly spaced perforations 50, which are now commonly known in the art as rack holes, and are used to uniformly advance a music sheet when it is employed for duplicating purposes as a master roll. They, of course, may 110 be omitted. Situated next below them, in the figure, are a series of perforations 51, which collectively form an elongated opening, such as is indicative of a sustained note, and next below such perforations, two perforations 52, which are indicative of a note repeated.

Figs. 2, 3 and 4 of the drawings indicate the operation of the mechanism, Fig. 2 showing the first position before a key 20 115 is depressed, Fig. 3 the second position when the key is first depressed, and Fig. 4, the condition of the parts with the key depressed and held down. When the key is first depressed, the latch 46 on cam 44 is 120

released and immediately engages with one of the teeth on the toothed wheel 45. This causes a movement of the cam 44 to the right. Assuming now that the operator has 5 struck the key and immediately released it. When a key is struck, the coating bell cranks 24, 25, are thrown into the position shown in Fig. 3, and when released, return to the position shown in Fig. 2, *i. e.*, their 10 original position. Consequently the cam 44 will make but one complete revolution before the tail of the latch 46 is brought into engagement with the bell crank 24 and the latch released from engagement with the 15 toothed wheel 45, thus bringing the cam to rest. When the cam has described one-half of a revolution, its rising periphery acting on the upper end of the trip lever 43 has moved such lever, and released the latch 42 20 on the eccentric 33 on shaft 26 which engages toothed wheel 41, thereby moving eccentric 33 and causing the forward movement of reciprocation of a punch.

It will be seen that no movement of a 25 punch takes place in the period between the time the key is depressed and the time when the cam moved 180° or one-half of a revolution. This movement is graphically indicated by the spaces *a*, *b*, in Fig. 5, and 30 these spaces, it will be understood, represent a forward movement of the music strip, each space representing one-twentieth of an inch. A further movement of the paper takes place of one-fortieth of an inch after the 35 180° movement of the cam 44 before a hole is made in the music strip, because the eccentric 33 must again move through 180° to make the hole. This is shown in Fig. 5.

The arrows indicate the depression and 40 raising of the finger of the performer, and it will be seen from reference to Fig. 5, that one reciprocation of the punch forward is made after the finger is removed from the key; and further, that as the paper moves 45 four-twentieths of an inch for each complete rotary movement of the cam 44, the note holes 52 (indicative of single repeated notes), cannot possibly be placed in the music strip at a distance less than one-fifth 50 of an inch between centers. It will be observed that this condition is only possible, by means of the interposition of a time interval between the striking of a key and the time when the trip lever permits a punch to act. 55 It will be seen that when the initial movement is given by the depression of a key, the cam 44 moves through 180 degrees, punching movement then takes place, and that before the punch can again act, the cam must 60 again move through 180°, all told, 360 degrees, *i. e.*, 180 degrees from its punching position to its original position, and 180 degrees from its original position to its punching position.

65 The foregoing description has related

solely to the action when a key is struck and immediately released. Assuming now that the finger has struck a key and the key is held down. In such case, the perforation illustrated at 51 results. Under such condition, the bell crank 25 is held in the path of movement of the tail of the latch 46, the effect of which is to release the latch, and the cam 44 will stop in the position shown in Fig. 4, *i. e.*, with the highest point on its 70 cam surface bearing upon the trip lever 43. The latch 42 on eccentric 33, however, remains in engagement with the toothed wheel 41. Consequently, as long as the finger is held down, and this position of the parts is 80 preserved, the punch will continue to reciprocate.

It will be seen by reference to Fig. 5, the spaces *a*, *b*, *c*, *d*, representing the forward movement of the music strip, that *a*, *b*, is 85 the same as was described in relation to perforation 52, *i. e.*, before the first perforation was made, but that subsequently thereto, owing to the fact that the cam 44 is at rest, and the eccentric 33 reciprocated by the high 90 speed shaft 26, that a perforation is made, for each one-twentieth of an inch forward movement of the music strip, the perforations coöperating to form an elongated opening as shown at 51. Further, it will be observed, that each perforation is made within 95 less time than was required by the performer to play the note. For example, the time required to strike the key to produce perforation 51 is equal to time of six spaces, whereas 100 the time to perforate it is equal to the time of four spaces. This, of course, is due to the use of the controlling devices actuated by shaft 29.

What is true of the perforating operation 105 of the mechanism as shown in Figs. 1, 2, 3, and 4, as illustrated in Fig. 5, is also true of the mechanism illustrated in Figs. 6, 7, 8, 9 and 10. These figures illustrate how the time limit, described in relation to Figs. 1, 2, 110 3 and 4, may be interposed by other means.

Referring now to Fig. 6: In this figure, 115 29 indicates the slow speed shaft. Loosely mounted on this shaft, are a series of plates 55. These plates are loose on the shaft, but adapted to be thrown into engagement with the shaft, when released by the latches 56, by means of the rotating friction disks 57. 26, indicates the high speed shaft, and 34 the punches. 23, cord from keyboard. The 120 operation of these parts is as follows: When a cord 23 is depressed, a plate 55 is released. This plate under the action of a pair of friction disks 57, moves circumferentially to the right, and when it has described 180° 125 (the initial time limit), closes a circuit through spring clips 58, dynamo 59, and magnet 60, which actuates a bell crank 61, which in turn actuates a pendent cam 62, arranged over a punch 34. The punch is 130

held in a reciprocating frame 63, suspended from eccentrics 64, on the high speed shaft 26. The second time interval in this device occurs from the time the plate 55 breaks 5 the circuit through spring clips 58, until it can again make the circuit, *i. e.* has moved through 360°.

Referring to Fig. 7: In this view there is shown a tube 65. Situated in this tube are 10 a series of balls 66. Under these balls is arranged a shutter 67. A similar shutter 68 is at the bottom of the tube. These shutters are connected to bell cranks 69 and through cord 23 to a key of a piano. Located at the bottom of the tube are the contacts 70, 71. The punching mechanism shown is similar to that of Fig. 6. The operation of this form of device is as follows: When a key is depressed, the shutter 20 67 allows one of the balls 66 to drop by gravity, or accelerated, if desired, by any constant force in the tube. The time required for the ball to drop from its position at the top of a tube to the bottom of a 25 tube, represents the time interval between the striking of a key and the actuation of a punch through the closure of the circuit by a ball through the magnet 60, which controls the punch.

Referring now to Figs. 8, 9 and 10: In these figures, the perforating mechanism is shown as mounted on the top of an ordinary piano. In Fig. 8, the control of a latch 42 and an eccentric 33 is by means of a pneumatic bellows 75, which in turn is controlled 35 through a pneumatic valve 76, arranged in the path of movement of a hammer 77 of the piano action.

The details of the valve 76 are shown in 40 Figs. 12 and 13. When the key 20 is depressed, a hammer 77, is thrown forward. This hammer strikes a valve 76 opening it, which acting through a pneumatic 78 operates a bellows 75, thereby releasing a latch 45 42, and throwing a punch 34 into action. The time interval in this case is the time taken by the hammer, in moving from its position at rest, to the position where it opens the valve 76. As will be understood 50 by those familiar with piano mechanism, a sustained note may be obtained by holding down the key, which holds up a hammer as indicated in Fig. 11, to maintain the valve 76 open.

In Fig. 9, the cord 23 is connected at one 55 end to a key and at the upper end to a spring 80, which spring is connected to one arm of a weighted bell crank 81. In this construction, when a key is depressed, the 60 spring 80 is put under tension, and the time interval is due to the time required to bring the spring to the required tension to overcome the inertia of the weight on the end of the bell crank 81.

In Fig. 10, the cord 23 is connected to a 65 bell crank 83, one end of which forms a circuit closer adapted to coact with contacts 84, 85. 86 represents a highly inductive coil which lags the current in building up in the trip magnet 87. When a key is depressed, 70 the circuit through the contacts 84, 85, is closed, and by reason of the interpolated reactance, the action of the magnet 87 is retarded. This retardation is the time interval between the striking of the key and the 75 action of the punch.

I wish it understood that I do not limit myself to the various forms of mechanism described for introducing a time interval, as many different ways of accomplishing 80 this same result will suggest themselves to mechanics, electricians and others.

Having thus described my invention, what I claim and desire to secure by Letters Patent is:

85

1. The herein described method which consists in causing a previously measured period of time to elapse between the time the keyboard is struck and the time when said movement is recorded.

90

2. The herein described method which consists in causing a definite predetermined forward movement of the music strip to take place between the time of the striking of the key and the action of the recording 95 device.

3. The herein described method which consists in causing a definite predetermined forward movement of the music strip to take place between the striking of a key and 100 possible successive actions of the recording device.

4. The herein described method which consists in recording the time of depression of any key within a predetermined period 105 of time shorter than that during which the key is depressed.

5. The herein described method which consists in causing a definite predetermined period of time to elapse between the ending 110 of one recording operation and the beginning of another of the same note.

6. The herein described method of recording a performance upon a music strip which consists in causing a previously 115 measured period of time to elapse between possible successive recordings of the same note.

7. The herein described method of recording a performance upon a music strip, which 120 consists in introducing a previously measured period of time between the successive recordings of any note.

8. The herein described method of recording a tone, which consists in making a 125 record in a period of time shorter, by a definite predetermined amount, than the time in which the tone was played.

9. A method of recording musical tones which consists in perforating a music sheet with a hole of the required length in less time, by a definite predetermined amount, than the finger of the operator remains upon the key in striking the note.
10. A step in a method of operation designed to produce a perforated music roll, which consists in causing a definite interval of time to elapse between the recording of two successive and similar notes, and such interval of time arranged to bear a fixed ratio to the speed at which such notes are recorded.
11. The herein described method which consists in causing a previously measured interval of time to elapse between the striking of a note and the recording of the note.
12. The herein described method which consists in causing a previously measured interval of time to elapse between the striking of a note and the recording of the note upon a moving strip of paper.
13. The herein described method which consists in recording upon a moving sheet of paper the striking of a note and causing a definite interval of time to elapse between recording two successive notes, this lapse of time bearing a fixed ratio to the speed at which the notes are recorded.
14. The herein described method which consists in recording a note within a period of time shorter than the time required to actuate the note key, the difference between said periods of time being predetermined and measured in terms of the speed of the recording device.
15. The herein described method of recording musical notes which consists in causing a definite predetermined minimum period of time to elapse between successive recordings of the same note.
16. The herein described method which consists in striking a note, then causing a definite predetermined interval of time to elapse before the note is recorded, then recording the note and causing a second predetermined interval of time to elapse after the note is recorded and before the same note can be again recorded.
17. The herein described method which consists in sounding a note, then recording the note within a period of time, shorter by a given amount, than the time required to sound the note.
18. The herein described method which consists in sounding a note, then recording the note within a period of time, shorter by a predetermined minimum amount, than the time required to sound the note.
19. The herein described method which consists in playing a note, then making a record of the note played within a period of time shorter, by a predetermined amount, than the time required to play the note.
20. The herein described method which consists in performing a portion of a musical composition, then making a record of the performance within a period of time shorter, by a predetermined amount, than the time required in performing such portion of the composition.
21. The herein described method which consists in selectively playing a note to be recorded, then recording the note within a period of time shorter, by a predetermined minimum amount, than the time required in selectively playing the note.
22. The herein described method which consists in causing a definite predetermined period of time to elapse between the sounding actuation of a note and the recording of the note.
23. The herein described method which consists in causing a predetermined period of time to elapse after the selection of a note and before the note is recorded.
24. The herein described method which consists in sounding a note, then recording the note upon a music strip, then giving the music strip a definite forward movement after the note is recorded.
25. The herein described method which consists in sounding a note, then recording the note upon a music strip, and causing the strip to advance a definite minimum amount after the note is recorded.
26. The herein described method which consists in playing a note, then recording the note upon a music strip, and causing a definite minimum advance of the strip after the note is recorded.
27. The herein described method which consists in causing a predetermined advance of the music strip between the ending of one recording operation and the beginning of another of the same note.
28. The herein described method which consists in causing a predetermined advance of the music strip between possible successive recording operations for the same note.
29. The herein described method which consists in causing a predetermined advance of the music strip after a note is recorded and before another can be recorded.
30. The herein described method which consists in causing a predetermined period of time to elapse after a note is recorded and before another note can be recorded.
- In testimony whereof, I affix my signature, in the presence of two witnesses.
